United States Patent Office

Des. 203,174
Patented Dec. 14, 1965

203,174

BURET OR SIMILAR ARTICLE

Ludwig Luft, Old Winter St., Lincoln, Mass.

Filed May 17, 1965, Ser. No. 85,294

Term of patent 14 years

(Cl. D16—1)

Fig. 1

Fig. 2

Fig. 3

Fig. 1

Fig. 5

Fig. 4

Fig. 6

FIG. 1 is a front elevation of a buret or similar article, showing my new design;

FIG. 2 is a side elevation viewed from the right hand side of FIG. 1;

FIG. 3 is a top view;

FIG. 4 is a rear elevation;

FIG. 5 is a side elevation viewed from the left hand side of FIG. 1; and

FIG. 6 is a bottom view.

The dominant features of my new design reside in the full line portion of the drawings.

I claim:

The ornamental design for a buret or similar article, substantially as shown and described.
